UNITED STATES PATENT OFFICE

2,482,135

FUSE

Charles B. Winkle, Salt Lake City, Utah

Application February 13, 1945, Serial No. 577,716

6 Claims. (Cl. 102—70)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to land mines, and more particularly to land mines adapted to be set for explosion at a predetermined temperature.

A main objective of this invention is to provide a land mine which may be effectively concealed and which is preset to explode without any required mechanical actuation, but merely by a change in temperature, such as a seasonal change in ambient temperature.

A further object of this invention is to provide a land mine adapted to be concealed in evacuated areas which will explode at a definite temperature change and cause destruction to enemy installations.

Further objects of this invention will become apparent from the following description and claims and from the accompanying drawings, wherein:

Figure 1 is a vertical cross-sectional view of a land mine according to this invention.

Figure 2 is a detail view of an adjusting screw and indicator means used in presetting the land mine of this invention.

Referring to the drawings, 1 designates the housing for the main explosive charge 2 of a land mine. Appropriately secured to the top wall of housing 1 is an auxiliary housing 3 containing a detonating assembly. Said detonating assembly comprises a tubular sleeve 4 threadedly engaged with the bottom wall of auxiliary housing 3 and extending into housing 1. At the bottom end of sleeve 4 a booster container 5 is threadedly secured to sleeve 4, said container carrying a booster charge 6 adapted to set off main charge 2 when exploded.

Mounted in an appropriate recess provided in the top end of sleeve 4 is a percussion cap 7 which is adapted to explode booster charge 6 when detonated. Flash passage 8 in sleeve 4 provides communication between percussion cap 7 and booster charge 6.

Percussion cap 7 is adapted to be detonated by a firing pin 9 carried on a striker arm 10 biased to striking position by a strong spring 11. Striker arm 10 is pivotally mounted on a rod 12 secured to the wall of auxiliary housing 3 and adapted to be forced from the normal position shown in Fig. 1 to the dotted striking position by the action of spring 11 when said striker arm is released. A safety pin 13 normally holds striker arm 10 in safe position.

2

A lever on detent member 14 is pivotally mounted on shaft 15 secured to the walls of housing 3, said lever member 14 being provided with a first arm portion 16 normally slightly overlying the end portion of striker arm 10 in detent relationship therewith, and a second arm portion 17 normally bearing against one end portion of a bimetal thermostat arm 18 whose other end portion is secured to a resilient mounting bracket 19 fastened to the bottom wall of auxiliary housing 3. The initial setting of the position of thermostat arm 18 may be adjusted by rotating a screw bolt 20 which extends through the wall of housing 3 into threaded engagement with a flange 21 provided on an extension of bracket 19. The surface of the outer wall of housing 3 adjacent the head of bolt 20 may be calibrated in degrees of temperature as shown in Figure 2, so that a pointer 22 marked on the bolt head may be set opposite a desired temperature value to indicate the value of change of ambient temperature at which bimetal arm 18 will allow lever 14 to move to a release position with respect to striker arm 10 so as to allow said arm 10 to be swung by spring 11 to detonate cap 7.

In setting the mine, a suitable concealed location is selected, bolt 20 is adjusted so that pointer 22 is positioned opposite the desired temperature change for detonation, and safety pin 13 is removed. The location of the mine should be selected with due regard to minimizing the temperature differential between the desired value of ambient temperature for detonation and the actual temperature at the mine site.

When the ambient temperature reaches the predetermined value, bimetal arm 18 deflects sufficiently to allow lever 14 to move so as to allow striker arm 10 to move past detent arm 16 under the pressure of spring 11 and to cause striker arm 10 to swing firing pin 9 into forceful contact with percussion cap 7. Cap 7 is detonated, causing booster charge 6 to explode and to set off main charge 2.

Although as disclosed in the present embodiment, the bimetal element will operate to release the striker arm responsive to a change in temperature in one direction, for example, a drop in temperature, it is evident that said bimetal element may be reversed so as to function upon a rise in temperature, if so desired.

While a specific embodiment of a temperature controlled land mine has been disclosed in the foregoing description, various modifications within the spirit of the invention will occur to those skilled in the art. Therefore, it is intended that

no limitations be placed on the invention other than as defined by the scope of the appended claims.

I claim:

1. A fuze comprising an explosive charge detonating means movable in a path to detonate said charge, a pivoted detent having one portion normally interposed in said path to prevent detonating movement of said detonating means, said detent having a second portion, a bimetallic element engaging said second portion to restrain pivotal movement of said detent means and movable under change of temperature to release the same, a support for said element said support being adjustable to vary the extent of movement of said element necessary to release said detent.

2. The combination as specified in claim 1, and means graduated in terms of temperature change for so adjusting said support.

3. A fuze comprising a sleeve having a flash passage therein, a detonator seated in one end of the sleeve and positioned to ignite an explosive charge, a spring driven striker arm positioned adjacent the detonator, a thermostatically controlled releasing mechanism comprising a substantially resilient mounting bracket having an inturned end fastened to the base member of the fuze housing, a rectangularly shaped bimetallic element attached to said bracket adjacent said inturned end and having releasable engagement with a detent means, a temperature preset screw supported in a vertical wall of said fuze housing and in threaded engagement with the free end of said bracket, said detent means interposed between the striker arm and the thermostatically controlled releasing mechanism whereby the striker arm is held in an inoperative position only until a predetermined ambient temperature is reached.

4. A fuze comprising a sleeve having a flash passage therein, an explosive charge disposed at one end of the sleeve and in alignment with the flash passage, a detonator seated in the other end of the sleeve and positioned to fire through the flash tube, a spring driven striker arm mounted outside of the sleeve, a thermostatically controlled releasing mechanism adjacent the striker arm, said thermostatically controlled releasing mechanism comprising a substantially resilient mounting bracket having an inturned end fastened to the base member of the fuze housing, a rectangularly shaped bimetallic element attached to said bracket adjacent said inturned end and having releasable engagement with a detent interposed between the thermostatically controlled mechanism and the striker arm and operative to hold the striker arm in an inoperative position only until a predetermined ambient temperature change occurs, and manually operable means for presetting the thermostatically controlled mechanism, said manually

operated means comprising a temperature preset screw, the head end supported in a vertical wall of said fuze housing and the thread portion in adjustable engagement with the opposite end of said mounting bracket.

5. A fuze comprising a sleeve having a flash passage therein, an explosive charge disposed at one end of the sleeve and in axial alignment with the flash passage, a detonator seated in the other end of the sleeve and positioned to fire through the flash tube, a spring driven striker arm pivoted outside of the sleeve, a movable detent for holding the striker arm in inoperative position, a thermostat comprising a bimetallic arm normally disposed in the path of movement of the detent and movable away from the detent to release said detent when affected by a change of ambient temperature, and means for adjusting the thermostatic arm to permit release of the movable detent at a predetermined ambient temperature.

6. A temperature-responsive detonator for explosive mines comprising a rotatable arm carrying a firing pin movable in a path from a first to a second, or detonating position, spring means urging said rotatable arm into said second position, a pivoted detent adapted in one position to engage said rotatable arm and retain the same in its said first position, and in another position to release said rotatable arm, a bimetallic element normally interposed in the path of pivotal movement of said detent to contact and hold the same in said one position, against the urge of said spring means, and to move out of said path in response to a definite change of ambient temperature, and a support for said element adjustable to vary the length of the path of contact of said element and detent whereby to selectively vary the change in ambient temperature necessary to release said detent and said rotatable arm.

CHARLES B. WINKLE.
